CLAIM

The ornamental design for the bottle closure, as shown and described.

DESCRIPTION

FIG. 1 is a perspective view of a bottle closure incorporating the design of my new invention;

FIG. 2 is a front elevation view thereof;

FIG. 3 is a left side elevation view thereof, depicting a bottle in phantom;

FIG. 4 is a left side elevation view thereof;

FIG. 5 is a rear elevation view thereof;

FIG. 6 is a right side elevation view thereof;

FIG. 7 is a top plan view thereof; and,

FIG. 8 is a bottom plan view thereof.

The phantom lines in the figures of the bottle closure are for illustrative purposes only and form no part of the claimed design.
